US00D660246S

(12) **United States Design Patent**
Bodmann et al.

(10) **Patent No.:** **US D660,246 S**
(45) **Date of Patent:** **** May 22, 2012**

(54) **FEMALE COMMUNICATION CONNECTOR
OF AN AUTOMATION DEVICE**

(75) Inventors: **Douglas R. Bodmann**, Shaker Heights, OH (US); **Chee Lim Wong**, Singapore (SG)

(73) Assignee: **Rockwell Automation Technologies, Inc.**, Mayfield Heights, OH (US)

(**) Term: **14 Years**

(21) Appl. No.: **29/405,842**

(22) Filed: **Nov. 7, 2011**

Related U.S. Application Data

(63) Continuation of application No. 29/385,607, filed on Feb. 16, 2011, now Pat. No. Des. 650,755.

(57) **CLAIM**

The ornamental design for a female communication connector of an automation device, as shown and described.

DESCRIPTION

FIG. 1 is a left side perspective view of a female communication connector of an automation device showing our new design;

FIG. 2 is a right perspective view thereof; and,

FIG. 3 is a front elevational view thereof.

The even-broken line shown in the figure drawings is included for the purpose of illustrating environment and forms no part of the claimed design. The dash-dot broken line represents the boundary of the claimed design.
